ROCK CORE DRILL HEAD

John H. Howard, Huntington Park, and Alfred C. Catland, Alhambra, Calif.; said Catland assignor to Globe Oil Tools Company, Los Nietos, Calif., a corporation of California

Application February 4, 1935, Serial No. 4,848

10 Claims.

(Cl. 255—72)

This invention relates to well drilling tools and has particular reference to core drills employed in the rotary method of well drilling. A general object of the invention is to provide a practical

5 efficient core drill that is very long wearing.

In well drills having roller cutters and particularly in rock core drills the thrust bearings or washers at the ends of the cutters are subjected to a great amount of wear. Relatively slight wear of 10 the thrust washers allows the cutters to move away from the wall of the well bore or away from the core as the case may be, and as the wear increases the drill rapidly loses gauge or drills an undersized bore and core. When the wear of the 15 thrust parts or washers of the cutter mountings becomes excessive the body or head of the drill wears away and in some instances the cutter assemblies are lost in the well.

Another object of the present invention is to 20 provide a core drill head in which the cutters are shaped and related so that they are braced or supported to a substantial extent against the principal end thrusts by their contact with the earth formation whereby the thrust bearing 25 parts of their mountings are relieved of considerable wear, making the tool long wearing and capable of drilling a bore to gauge for a maximum distance.

Another object of the invention is to provide 30 a core drill head that comprises a plurality of spaced inner and outer roller cutters that are shaped and related to form an annular ridge of earth formation at the bottom of the well bore that is engaged by the inner ends of the cutting parts of the outer cutters to brace or support 35 the outer cutters against the heavy inward thrusts and is engaged by the outer ends of the cutting parts on the inner cutters to support the inner cutters against the heavy outward thrusts. 40 The annular ridge left or formed by the cutters is engaged or acted on by the cutters in a manner to partially balance or compensate for the principal heavy end thrusts to which the cutters are subjected thus relieving the thrust receiving 45 members of the cutter mountings of considerable wear.

Another object of the invention is to provide 50 a core drill head of the character mentioned in which the forming and cutting away of the thrust compensating ridge of earth formation does not retard the drill or detract from its efficient cutting action.

The various objects and features of our invention 55 will be fully understood from the following detailed description of a typical preferred form

and application of the invention, throughout which description reference is made to the accompanying drawing, in which:

Fig. 1 is a side elevation of a core drill embodying a head whose cutters are formed and related as provided by the invention. Fig. 2 is an enlarged vertical detailed sectional view of the lower portion of the drill and the cutter head. Fig. 3 is an enlarged fragmentary vertical detailed sectional view of a portion of the head 10 illustrating an outer cutter and its mounting. Fig. 4 is a view similar to Fig. 3 illustrating an inner cutter and its mounting and Fig. 5 is a bottom elevation of the drill head.

The present invention is primarily concerned 15 with the shape, mounting and relating of the roller cutters of a well drill and is adapted to be applied to or embodied in drills varying considerably in character. In the following detailed disclosure we will describe the invention as embodied in the head of a more or less typical core 20 drill, it being understood that the invention is not to be construed as limited or restricted to the specific form or application about to be described.

The core drill illustrated in the drawing includes an outer barrel 10 having a lifter sub 11 connected with its upper end. A threaded pin 12 is provided on the upper end of the sub 11 to facilitate the connection of the drill with a 30 drill collar or other part of an operating string. A sub 13 on the lower end of the outer barrel 10 carries a bit head sub 14. A pin 15 projects from the lower end of the sub 14 to carry the drill head. The drill includes an inner barrel 35 16 which extends longitudinally through the outer barrel 10. The lower end of the inner barrel 16 is screw threaded in the opening 17 of the sub 14 and is open to receive the core. A core catcher 18 is arranged in the opening 17 to 40 retain the core when the drill is withdrawn from the well. The core catcher 18 includes slips 19 that are actuated inwardly to grip the core C by cooperating with the inclined lower wall of the opening 17. The inner barrel 16 is spaced 45 from the interior of the outer barrel 10 leaving an annular fluid passage 20. Spaced longitudinal ports 21 are provided in the wall of the sub 14 to carry the circulation fluid downwardly from the passage 20 to the bit head.

The present invention includes, generally, a tubular shoe or bit head body 22 and a plurality of inner cutters A and outer cutters B and B'.

The shoe or body of the head is an annular or tubular member having a central longitudinal

opening 23. A threaded socket 24 is provided in the upper end of the body 22 to receive the pin 15. A plurality of circumferentially spaced ribs or wings 25 is provided on the lower portion of the body 22. The spaces between the wings 25 constitute channels 26 for passing the upwardly flowing circulation fluid as it flows around the lower end of the body. Spaced sockets or recesses 27 and 28 are provided in the lower end of the body 22 to carry the cutters A and B and B'. The recesses 27 and 28 are located so that the wings 25 constitute the body parts which form or define the outer walls of the recesses. The inner and outer walls of the recesses 27 are preferably inclined downwardly and inwardly with respect to the longitudinal axis of the drill. The inner and outer walls of the recesses 28 are preferably inclined downwardly and outwardly with respect to the axis of the tool. Bosses 29 are provided on the inner walls of the recesses 27 and the outer walls of the recesses 28. The invention contemplates the employment of various numbers of inner and outer cutters A, B and B'. In the particular drill head illustrated there are two diametrically opposite recesses 27 for carrying two cutters A and two pairs of recesses 28 spaced between the recesses 27 for carrying four cutters B and B'. An annular groove 30 is provided in the upper end of the body 22 to register with the lower ends of the ports 21. Spaced longitudinal ports or passages 31 extend through the wall of the body 22 from the groove 30 to the upper ends of the recesses 27 and 28 to discharge the circulation fluid downwardly against the cutters A, B and B', respectively.

The cutters A and B are rotatably supported or mounted in the recesses 27 and 28 to rotate about axes inclined relative to the axis of the drill and to project from the lower end of the head to act on the earth formation. In accordance with the broader aspects of the invention the cutters A, B and B' may be rotatably supported or mounted in any suitable manner. In the drawing we have illustrated the cutters A, B and B' rotatably mounted or supported by the means fully described and claimed in our copending application entitled Core drill head, Serial No. 4,846, filed February 4, 1935, which has matured into Patent No. 2,058,156 granted Oct. 20, 1936.

The cutter mounting means illustrated includes pins 32 extending through the recesses 27 and 28. One end of each pin 32 is threaded in an opening 33 in the body 22 and the opposite headed or enlarged ends of the pins are carried in openings 34. Bushings 35 are provided on the pins 32. Each bushing 35 has a radially projecting annular flange 36 at one end to bear against the boss 29 on the wall of the recess. The openings of the bushings 35 where they pass through the flanges 36 have flat walls 37. The flat walls 37 on the interiors of the bushings 35 cooperate with flat faces 38 on the pins 32 to hold the bushings against rotation. Thrust washers 39 are provided on the pins 32. The thrust washers 39 on the pins 32 carrying the inner cutters A bear against the outer walls of the recesses 27 while the washers 39 on the pins 32 carrying the outer cutters B and B' bear against the inner walls of the recesses 28. Roller bearings 40 are provided on the bushings 35 to rotatably support the cutters A, B and B'.

The inner cutters A are provided to act on the earth formation to form the inner portion of the well bore and to trim the core C. The cutters A are in the nature of roller cutters that are

substantially cylindrical in their general configuration. Each cutter A has a central longitudinal opening 41 provided at one end with an enlargement or socket 42. The inner cutters A are rotatably supported in the recesses 27 by the bearing means just described to rotate about axes inclined downwardly and outwardly relative to the longitudinal axis of the drill. The cutters A are arranged to be rotatably supported on the bushings 35 through the rollers or bearings 42. The flanges 36 on the bushings are received in the sockets 42 and the outer ends of the cutters A have thrust bearing cooperation with the washers 39. The cutters A mounted in this manner project downwardly beyond the lower end of the body 22 and project into the opening 33 to trim the core C.

The inner cutters A are provided with peripheral cutting teeth or cutting parts 43. The cutting parts 43 extend axially of the cutters and may be continuous. The cutting parts 43 are preferably spiraled and it is preferred to pitch the parts 43 of one cutter A in a right hand direction and the parts 43 of the other cutter A in a left hand direction. The inner ends or corners 44 of the cutting parts 43 are cut away or bevelled to properly and effectively trim the core C. The ends 44 of the cutting parts are substantially vertical when they come into contact with the earth formation to trim the core. The principal axial cutting edges of the parts 43 are inclined where they contact the earth formation to provide the bottom of the well bore with a downwardly and outwardly inclined wall portion 45.

In accordance with the invention the outer corners or ends 46 of the cutting parts 43 are cut away or bevelled to present downwardly and inwardly inclined edges or faces as they engage the earth formation. These ends 46 of the cutting parts cooperate with the earth formation to form a downwardly and inwardly inclined wall or surface 47 on the bottom of the well bore surrounding the surface 45. The ends 46 of the cutting parts 43 are inclined in the opposite direction to the principal longitudinal edges of the cutting parts and their engagement with the surface 47 of the earth formation balances and counteracts the outward end thrusts resulting from cooperation of the principal cutting edges and the ends 44 of the parts 43 with the formation. The contact of the ends 46 of the cutting parts with the surface 47 relieves the thrust washers 39 of a substantial amount of end thrusts to which they might otherwise be subjected.

The cutters B and B' are the outer cutters for acting on the outer portion of the bottom of the well bore and for cutting the bore to size. The outer cutters B and B' are substantially frustoconical roller cutters having flat opposite ends and inclined or tapered peripheries. Each outer cutter B and B' has a central longitudinal opening 50 having a socket 51 in its inner end. The cutters B and B' are mounted on the pins 32 extending through the recesses 28 through the medium of the bushings 35 and bearings 40. The flanges 36 of the bushings 35 are received in the sockets 51. The inner ends of the cutters B and B' bear against the washers 39. In accordance with the invention the outer cutters B and B' are rotatable about downwardly and inwardly inclined axes. The pins 32 extending through the recesses 28 are inclined downwardly and inwardly to be substantially normal to the inner and outer walls of the recesses.

Axially extending teeth or cutting parts 53 are provided on the outer cutters B and B'. Each pair of adjacent outer cutters includes a cutter B having straight axial cutting parts 53 and a cutter B' having spiralled cutting parts 53^a. The spiralled cutting parts 53^a of the cutters B' at the opposite sides of the body 22 are preferably pitched in opposite directions. The frusto-conical cutters B and B' in being rotatable about 5 downwardly and inwardly inclined axes have their cutting parts 53 and 53^a substantially horizontal where they come into contact with the earth formation at the bottom of the bore to provide the bottom of the well bore with a substantially 10 flat horizontal wall or surface 54. The outer corners or ends 55 of the cutting parts 53 and 53^a are bevelled or pitched to properly cooperate with the formation at the side wall of the well bore. The ends 55 of the cutting parts are 15 pitched to be substantially vertical when in active engagement with the side wall of the well bore. It is a feature of the invention that the inner ends 56 of the cutting parts 53 and 53^a are pitched or inclined to act on the earth formation 20 and form a downwardly and outwardly inclined surface 57 at the bottom of the bore whose upper end joins the surface 41 to form or leave an annular ridge R. The engagement of the ends 56 of the cutting parts B and B' with the outer 25 surface 57 of the ridge R balances or counteracts the heavy inward thrusts put upon them by their engagement with the bottom and side walls of the well bore, thus relieving the washers 39 of these end thrusts.

35 During operation of the core drill the drilling string or operating string is rotated in the usual manner and fed downwardly so that the cutters A, B and B' act on the formation to drill the well bore and form the core C. The inner cutters A project from the bottom of the body 22 so that their cutting parts 43 engage the formation at the bottom of the bore to cut away the formation at the surface 45. The inner ends 44 of the cutting parts 43 trim the core to pass into the opening 23 with the proper clearance. The outer ends 46 of the cutting parts 43 act on the formation at the inner surface 41 of the ridge R. This engagement of the ends 46 with the surface 41 supports the inner cutters A against the outwardly directed end thrusts to which they are subjected because of their engagement with the core and the formation at the surface 45. The outer cutters B and B' project beyond the lower end of the body 22 so that their cutting parts 53 and 53^a act on the formation at the surface 54 to drill the outer portion of the well bore. The outer ends 55 of the outer cutters B and B' engage the side wall of the bore and operate to cut the bore to the proper gauge. The inner ends 56 of the cutting parts 53 and 53^a engage the formation at the outer surface 57 of the ridge R. This engagement of the ends 56 with the surface 57 balances or compensates for the engagement of the ends 55 and the principal edges of the cutting parts 53 and 53^a with the formation thus relieving the thrust washers 39 of an appreciable amount of end thrusts.

70 The sets of cutters A and the sets of cutters B and B' are related and shaped to provide or leave the annular ridge R at the bottom of the well bore which constitutes a thrust ridge or abutment against which the ends of the cutting parts bear to relieve the thrust parts of the cutter mountings of end thrusts. The forming of the 75 ridge R and the presence of the ridge R at the

bottom of the bore do not in any way interfere with the operation or cutting action of the drill. The thrust washers 39 and the other parts of the cutter mountings in being relieved of end thrusts through the cooperation of the ends of the cutting parts with the ridge R are very long wearing to prevent end play or movement of the cutters. The ridge R of earth formation materially aids in supporting the cutters against end thrusts so that the cutter mountings are capable of supporting the cutters in positions to drill the bore to the proper gauge and to drill the core C to size for a maximum length of bore or hole.

Having described only a typical form and application of our invention, we do not wish to be limited or restricted to the specific forms and applications herein set forth, but wish to reserve to ourselves any modifications or variations that may appear to those skilled in the art or fall within the scope of the following claims.

Having described our invention, we claim:

1. A well drill including a body, a cutter supported on the body for rotation and projecting from its lower end, cutting parts on the cutter for acting on the formation at the bottom and side wall of the bore, and bevelled inner end faces on the cutting parts engaging the formation to support the cutter against the end thrusts imposed by its engagement with the bottom and side wall of the bore.

2. A core drill head including an annular body, a substantially frusto-conical cutter projecting from the lower end of the body and rotatable about an axis inclined downwardly and inwardly relative to the longitudinal axis of the drill, peripheral cutting parts on the cutter for acting on the formation at the bottom wall of the bore, and beveled inner end faces on the cutting parts pitched relative to both the inner end of the cutter and the longitudinal edges of the cutting parts for engaging the formation to support the cutter against inward thrusts.

3. A core drill head including an annular body, a substantially frusto-conical cutter projecting from the lower end of the body and rotatable about an axis inclined downwardly and inwardly relative to the longitudinal axis of the drill, peripheral cutting parts on the cutter for acting on the formation at the bottom wall of the bore, outer end faces on the cutting parts for acting on the side wall of the bore, and inner end faces on the cutting parts inclined downwardly and outwardly relative to the inner end of the cutter for engaging the formation to counteract the inward thrusts on the cutter.

4. A core drill head including, a tubular body, a cutter projecting from the lower end of the body and supported thereon for rotation, peripheral cutting parts on the cutter having inner ends for trimming a core for reception by the body, and relatively blunt outer end faces on the cutting parts pitched relative to the outer end of the cutter and the principal cutting edges of the cutting parts to be inclined downwardly and inwardly when they act on the formation to support the cutter against outward thrusts.

5. A core drill head including a tubular body, a substantially cylindrical cutter projecting from the lower end of the body and rotatable about a downwardly and outwardly inclined axis, axially extending cutting parts on the cutter having inner ends for trimming a core for reception by the body, and outer end faces on the cutting parts pitched relative to the outer end of the cutter and the principal cutting edges of the cutting

parts to be inclined downwardly and inwardly relative to the longitudinal axis of the body as they come into engagement with the formation to support the cutter against outward thrusts.

5 6. A core drill head including a tubular body, an outer cutter supported on the body for rotation and projecting from the body to engage the formation at the bottom of the bore and to cut the bore to size, said outer cutter having inwardly 10 facing cutting parts to act on a surface of the formation to counteract the inward thrusts on the cutter, and an inner cutter supported on the body for rotation and projecting from the body to engage the formation at the bottom of the bore and to trim a core for reception by the body and 15 having outwardly facing cutting parts inclined downwardly and inwardly when they act on a surface of the formation and operable to counteract the outward thrusts on the inner cutter, said 20 surfaces defining a ridge on the bottom of the bore.

7. A core drill head including a tubular body, an outer cutter supported on the body for rotation about a downwardly and inwardly inclined 25 axis and projecting from the body to engage the formation at the bottom of the bore and to cut the bore to size, said outer cutter having inwardly facing cutting parts inclined relative to the inner end of the cutter and operable to act on a surface 30 of the formation to counteract the inward thrusts on the cutter, and an inner cutter supported on the body for rotation about a downwardly and outwardly inclined axis and projecting from the body to engage the formation at the bottom of the bore and to trim a core for reception by the body 35 and having outwardly facing cutting parts inclined downwardly and inwardly when they act on a surface of the formation and operable to counteract the outward thrusts on the inner cutter, said 40 surfaces defining a ridge on the bottom of the bore.

8. A core drill head including a tubular body, an outer cutter of substantially frusto-conical 45 configuration supported on the body for rotation and projecting from the body to engage the

formation at the bottom of the bore and to cut the bore to size, said outer cutter having inwardly facing cutting parts inclined relative to the inner end of the cutter and operable to act on a surface of the formation to counteract the inward thrusts on the cutter, and an inner cutter of substantially cylindrical configuration supported on the body for rotation and projecting from the body to engage the formation at the bottom of the bore and to trim a core for reception by the body and 10 having outwardly facing cutting parts inclined downwardly and inwardly when they act on a surface of the formation and operable to counteract the outward thrusts on the inner cutter, said 15 surfaces defining a ridge on the bottom of the bore.

9. A well drill including a body, a cutter supported on the body for rotation and projecting from its lower end, and cutting parts on the cutter having longitudinal cutting edges for acting on the formation at the bottom of the bore and that are substantially horizontal when in contact with the formation at the bottom of the bore, outer faces for acting on the side wall of the bore, and inner faces at the inner ends of the said longitudinal cutting edges inclined downwardly and outwardly relative to both the said longitudinal cutting edges and the inner end of the cutter when in contact with the formation to form and bear on a correspondingly inclined surface on the 30 formation to support the cutter against inward thrusts.

10. A core drill head including, a tubular body, a cutter projecting from the lower end of the body and supported thereon for rotation, cutting faces 35 on the inner end of the cutter for trimming a core for reception by the body, and cutting faces on the outer end of the cutter inclined downwardly and inwardly when they act on the formation and pitched at more than 90° to the axis of 40 rotation of the cutter to compensate for the end thrusts imposed on the cutter by the first mentioned cutting faces.

JOHN H. HOWARD.

ALFRED C. CATLAND.
